UNITED STATES PATENT OFFICE.

THEODORE B. THOMAS, OF QUINCY, MASSACHUSETTS.

LOCKING MEANS FOR AUTOMOBILES.

1,193,737.

Specification of Letters Patent. Patented Aug. 8, 1916.

Application filed February 11, 1916. Serial No. 77,744.

To all whom it may concern:

Be it known that I, THEODORE B. THOMAS, a citizen of the United States, residing at Quincy, in the county of Norfolk and State of Massachusetts, have invented an Improvement in Locking Means for Automobiles, of which the following is a specification.

This invention relates to locking-means for the steering-gear of automobiles.

The invention has for its object the construction of an improved form of locking means which is very simple and may be easily and cheaply manufactured, and easily applied to existing machines without the assistance of a machinist or skilled workman; will securely hold the steering-wheel against rotary movement when in locking engagement therewith, and when out of engagement therewith may be held or locked, if desired, in another position which will not interfere with the free movements of the driver.

The device comprises a clamping element adapted to be secured to the steering-post or other fixed support having a screw-eye by which it is held in adjusted position thereon, and a set of links arranged to be extended from said clamping element to and over one of the spokes of the steering-wheel, one of the links of the set being loosely mounted on the shank of the screw-eye, and another link of the set having an eye adapted to receive the eye-portion of the screw-eye, which eye-portion projects therethrough to receive the hook or movable locking-member of a pad-lock.

When the link-members are not in engagement with the spoke of the steering-wheel, 40 their position may be reversed, although they may be held in fixed position in substantially the same manner as when in locking engagement with the steering-wheel. When thus held they will not interfere with 45 the free movements of the driver.

To prevent rotative movement of the steering-wheel there should be no slack in the set of links employed and herein the set comprises three links of predetermined 50 lengths loosely connected together, the two end-most links of the set extending from the clamping element to the top of the wheel spoke, and the intermediate link extending across the top of the spoke.

Figure 1 is a side elevation of a locking

mechanism for the steering-gear of an automobile embodying this invention. Fig. 2 is a front elevation of the locking mechanism in its locking position. Fig. 3 is an enlarged sectional view on the dotted line 3—3. 60

10 represents the steering-post or other fixed support, and 12 the steering-wheel. A clamping element is adapted to be arranged on the steering-post which, as here shown, consists of an encircling member 13, having 65 two ears or cheek pieces 14 and 15, which are extended outwardly and in approximately parallel relation. These ears each have a hole through them as 16, 17, which holes are arranged in alignment to receive the shank 70 18 of a screw-eye, the hole 17 through the ear 15 being threaded for the engagement therewith of the threads on the shank of said screw-eye, and the shank of the screw-eye being made of such length that its eye-portion 19, or head, will engage the outer face of the ear 14, so that upon a turning 75 movement of said screw-eye, said ears will be moved toward and from each other, thereby to admit of frictionally binding the 80 encircling member in fixed position on the post.

The encircling member is made of such length as to embrace the post and also provide a space between the ears 14 and 15, so 85 that in said space a portion of the shank of the screw-eye is exposed. On said exposed portion of the shank 18 of the screw-eye one end of a link 20 is loosely mounted, it having an eye for engagement with said 90 shank, and said link is made of a length to span the distance between the clamping element and steering-wheel and to terminate just above the top of one of the spokes 95 thereof. The upper end of said link 20 is loosely connected to one end of another or shorter link 21, which is adapted to be extended at right angles thereto and to extend across the top of the spoke. The other end of said shorter link 21 is loosely connected to the upper end of another long link 22, which extends downward substantially in parallel relation with the link 20, and the lower end of said link 22 has an elongated eye 23 adapted to receive the eye-portion 19 100 of the screw-eye, said eye-portion projecting therethrough far enough to admit of the hook or other movable member 25 of a pad-lock 26 being thrust therethrough, thus to 105 lock the component parts. It is of impor- 110

tance that the ears, or at least one of them, shall extend a considerable distance above the shank of the screw-eye, so as to form an abutment against which the lower end-portion of a link 20 will bear, thereby to limit the movement of the link mechanism in one direction. Movement of the link mechanism in the other direction is limited by the link 22, which is held at its lower end by the 10 hook-member of the pad-lock, and at its upper end by the short link 21. For it will be observed that the outer end of the link mechanism has a tendency to move in the arc of a circle about the clamping element as a 15 center, while the spoke of the wheel has a tendency to move in the arc of a circle about the center of the wheel. The above description refers to the structure when in locking engagement with the steering-wheel. When 20 the steering-wheel is unlocked said link-mechanism may be swung downward into the position shown by dotted lines Fig. 2, and in such position its link 22 may be again arranged on the eye-portion of the screw- 25 eye, and the pad-lock secured in place as heretofore, thereby locking it in its reversed position.

I claim:—

The locking-mechanism for the steering-gear of automobiles herein described, consisting of a clamping element adapted to be arranged on the steering-post comprising an encircling member with spaced apart ears and a screw-eye, a set of connected links adapted to be passed over a spoke of the 30 steering-wheel, one of the end-most links of the set being mounted on the shank of the screw-eye between the ears, and the other end-most link of the set having an eye 35 adapted to receive the eye-portion of the screw-eye, said eye-portion projecting therethrough to receive a pad-lock by which the component parts are locked.

In testimony whereof, I have signed my name to this specification, in the presence of 45 two subscribing witnesses.

THEODORE B. THOMAS.
